UNITED STATES PATENT OFFICE.

LEE KINGSLEY, OF SYRACUSE, NEW YORK.

HOLDER FOR ADHESIVE BINDERS.

1,072,859.

Specification of Letters Patent.

Patented Sept. 9, 1913.

Application filed November 28, 1911. Serial No. 662,895.

To all whom it may concern:

Be it known that I, LEE KINGSLEY, of Syracuse, in the county of Onondaga, in the State of New York, have invented new and useful Improvements in Holders for Adhesive Binders, of which the following, taken in connection with the accompanying drawings, is a full, clear, and exact description.

10 This invention relates to certain improvements in holders for adhesive binders, such as pasters, labels and similar articles of paper or other suitable material having one side coated with an adhesive for affixing checks to bills and for any other purposes to which these pasters may be applied.

15 The primary object is to provide simple means for holding or maintaining one or more stacks of collated pasters in position for convenient removal and application one by one to the article or articles to which they are to be applied without disturbing or disarranging the remaining pasters 25 of the stack.

20 Another object is to provide simple means for automatically feeding the pasters into position to be removed one by one.

25 Other objects and uses will be brought out in the following description:

In the drawings Figure 1 is a perspective view of the incased holder ready for shipment and containing a quantity of pasters. Fig. 2 is a similar perspective view of the 30 holder ready for use, the case being removed. Fig. 3 is a transverse vertical sectional view taken on line 3—3, Fig. 2 showing the case in dotted lines. Fig. 4 is a perspective view of the detached receptacle 40 for the pasters and feeding means. Fig. 5 is a perspective view of the detached paster retaining cap. Fig. 6 is a perspective view of the follower. Fig. 7 is a perspective view of one of the pasters inverted.

45 As shown in Figs. 1 to 3 inclusive, this holder comprises a receptacle —1— for receiving and retaining a series of stacked pasters —a—, a follower —2— and a spring —3—, said receptacle being provided with 50 a removable paster retaining cap —4— surrounding its upper open end. The receptacle —1— is adapted to be inclosed in a suitable case —5— for protecting the pasters in storage or transportation and for 55 this purpose its lower end is open and pro-

vided with bendable tongues or flanges —6— adapted to be bent or deflected under the bottom of the receptacle —1— to hold it in operative position. The receptacle —1— preferably consists of a rectangular 60 box of sheet metal or other suitable material open at the top for the reception of the pasters —a— which are slidable vertically therein and are fed upwardly through the open end of the receptacle and against 65 the retaining cap —4— by means of the follower —2— and spring —3— as the uppermost labels are removed one by one. The follower —2— may be made of paste board or any other suitable material of 70 slightly less area than the interior of the receptacle —1— so as to move freely therein and is spring pressed upwardly by the spring —3— upon which it rests, the lower end of said spring being engaged with the 75 bottom of the receptacle —1— as shown more clearly in Fig. 3. The upper side of the follower is preferably convexed or V-shaped transversely so as to impart a similar form to the paster —a— for feeding 80 the central portions thereof upwardly and foremost through the open end of the receptacle or rather through the opening in the retaining cap —4— and also for the purpose of retaining the pasters in more 85 perfect alinement or stacked arrangement. These pasters —a— which are preferably made of paper coated on one side with an adhesive are also rectangular in plan and of slightly less length than the corresponding 90 length of the interior of the receptacle but are normally of greater width than the corresponding width of said receptacle so that when folded, the tendency of the edges is to spread apart and to impinge against 95 the adjacent side of the receptacle, thereby frictionally holding them against undue upward displacement and at the same time allowing the upwardly arched central portions of the pasters to protrude through the 100 opening in the retaining cap —2—. This retaining cap is fitted with a frictional fit for removability upon the upper open end of the receptacle —1— and its opposite sides are provided with inwardly projecting 105 flanges —7— projecting some distance beyond the corresponding sides of the receptacle but spaced some distance apart to leave a central opening —8— through which the upwardly arched central portions 110

of the pasters may protrude, said flanges serving to engage the upper surface of the downwardly deflected sides of the uppermost paster to additionally hold the stack 5 against undue upward displacement, and at the same time allowing the central portion of the uppermost paster to protrude a sufficient distance through and above the opening —8— to permit it to be engaged 10 by the moistened fingers, whereby the uppermost paster may be slightly compressed and withdrawn upwardly without disturbing the underlying pasters. As each uppermost paster is thus withdrawn, the remaining pasters are advanced upwardly 15 through the medium of the follower —2— and spring —3—, thereby impinging the sides of the top paster against the flanges —7— of the retaining cap —4— which as 20 previously stated temporarily hold the stack against further upward movement against the action of the spring —3—. The upper portions of the opposite ends of the receptacle —1— are provided with guards 25 or guide plates —9— for engagement with the ends of the pasters to prevent accidental lateral displacement thereof.

The retainer —4— is preferably made of sheet metal and its flanges —7— serve as 30 limiting stops to prevent undue downward movement thereof on the receptacle, while its opposite ends as —10— are made to frictionally bind against the corresponding ends of the receptacle to hold the cap against upward displacement under the action of the spring —3— but may be withdrawn by hand 35 at any time, as, for example, when it is desired to refill the receptacle with pasters. When the receptacle is filled and the cap 40 —4— placed in operative position, it may be covered by the casing or cover —5— which telescopes with an easy sliding fit with said receptacle, the upper end being closed, while its lower end is provided with lips or 45 tongues —6— adapted to be bent under the bottom of the receptacle as shown in Fig. 3 to hold the cover in operative position.

In refilling the receptacle with pasters, the retaining cap —4— may be removed and 50 a suitable quantity of the pasters which are previously cut into the desired form are stacked together and inserted into the open end of the receptacle and upon the follower —2—, thereby pressing said follower downward against the action of the spring —3— after which the cap —4— may be replaced

to temporarily hold the stack of pasters against undue upward displacement.

What I claim is:

1. A holder for folded binders comprising a case having two of its opposite side walls spaced apart a considerably less distance than the length of the binder when flattened out for engaging the ends of said binders and holding them in a partially folded position with their apexes uppermost, and a follower within the receptacle and spring pressed upwardly and having its upper face V-shape to conform to and engage with the fold of the lowermost binder. 70

2. A holder for folded binders comprising a case having two of its opposite side walls spaced apart a considerably less distance than the length of the binder when flattened out for engaging the ends of said binders and holding them in a partially folded position with their apexes uppermost, and a cap fitted with a frictional sliding fit upon the upper end of the case and provided with opposite inwardly projecting flanges extending beyond the adjacent sides of the case and spaced some distance apart to form a lengthwise opening of substantially the same width as the binders and a follower within the case spring pressed upwardly and having a 85 V-shape upper face engaging in the fold of the lowermost binder for forcing the apexes of the uppermost binders through and above the opening in the cap. 80

3. A holder for adhesive binders comprising a case having two of its opposite upright sides parallel and spaced apart a distance less than the length of the binders, said binders being folded midway between their ends and stacked within the case with their ends 95 abutting against said parallel sides so as to force the apexes of the binders upwardly, the upper end of the case being provided with an opening and stop shoulders for engaging the opposite ends of the uppermost 100 binders, and a follower within the case spring pressed upwardly and having a V-shape upper face engaging in the fold of the lowermost binder for forcing the apexes of the binders upwardly through the open 105 top of the case.

In witness whereof I have hereunto set my hand on this 17th day of November 1911.

LEE KINGSLEY.
